METHOD AND APPARATUS FOR BLENDING
OR MIXING

Robert C. Hopkins, Alliance, Ohio

Application June 26, 1941, Serial No. 399,826

11 Claims. (Cl. 196—1)

This invention relates to methods and apparatus for blending or mixing materials, and, more particularly, is concerned with methods and apparatus for molecularly mixing liquids or liquid containing materials, and, specifically, the means and methods of my invention have been used for blending oils, such as bright stock, neutral stock, and pour depressant.

Heretofore, various processes and apparatus have been employed to blend or mix liquids or liquid containing materials, and with greater or less degrees of success. However, I have found that known means and methods are subject to considerable improvement. First, it has always been difficult to completely and accurately control the proportions and amounts of materials blended and to reproduce desired or previous blending conditions. Second, known methods and apparatus for blending have been open to the objection that a stirred mixture was obtained, not a complete molecular mixture or conglomerate of completely intermingled and broken down parts of the liquids or materials. Third, air, water vapor, or other gases entrapped in the materials or liquids have tended to retain themselves in the mixture which is often undesirable. Fourth, known apparatus has not adapted itself to use in mixing a large plurality of different materials and has been largely confined to a one operation purpose.

It is the general object of my invention to avoid and overcome the foregoing and other difficulties and objections heretofore associated with means for mixing and blending by the provision of improved methods and apparatus adapted to operation upon a wide variety of materials and of any given number, and which rapidly and inexpensively effect a most intimate mixing of the materials in exactly known and controlled amounts, and without the inclusion of air, water vapor, or other gases in the completely mixed product.

Another object of my invention is to provide relatively inexpensive, simple, long wearing, easily operated, and efficient apparatus for blending exactly measured and controlled amounts of a plurality of liquids or materials so as to produce a molecular conglomerate thereof and including substantially no entrapped gases.

Another object of my invention is the provision of apparatus of the indicated type in which by relatively simple changes or adjustments the apparatus is capable of handling and mixing any desired number of liquids or liquid bearing materials.

Another object of my invention is to provide

5 an improved process or method for rapidly, inexpensively, and efficiently mixing or blending a plurality of liquids and wherein the resulting mixture is free, or substantially free of entrapped gas and the liquids as mixed approach a molecular conglomerate stage.

10 Another object of my invention is the provision of a blending method whereby the liquids while under relatively high pressure are mixed with a cutting, attriting, grinding and milling action, followed by a sudden release of the pressure on the mixed liquids to separate substantially all the entrapped gases therefrom.

15 The foregoing and other objects of my invention are achieved by the provision of apparatus including a blending mill adapted to reduce the liquids to a molecular conglomerate by cutting, attriting, grinding, and milling, means for driving the mill at high speed, means for supplying controlled amounts of a plurality of liquids and under controlled relatively high pressures to the blending mill, a storage tank, means for discharging the output of the blending mill into the storage tank, and means for withdrawing gas from the top of the storage tank and for maintaining the inside of the tank under not greater than atmospheric pressure.

20 The method of my invention comprises passing a controlled and measured amount of one liquid to a mixing chamber, passing controlled and measured amounts of one or more additional liquids to the mixing chamber, maintaining the liquids under a relatively high pressure in the mixing chamber, reducing the liquids to a molecular conglomerate by cutting, attriting, grinding, and milling them while under pressure in the mixing chamber, passing the molecular conglomerate of liquids still under pressure to a storage tank, and suddenly releasing the pressure on the conglomerate as it is discharged into the storage tank so that any gas bubbles present explode or escape and the gas stays at the top of the tank and the liquid conglomerate falls into the bottom of the tank.

25 For a better understanding of my invention reference should be had to the accompanying drawing wherein Fig. 1 is a diagrammatic plan view of one typical embodiment of apparatus incorporating the principles of my invention; and Fig. 2 is a view generally similar to Fig. 1 but on a greatly reduced scale and illustrating a modification of my invention adapted to handle and blend a greater number of liquids than the form of the invention shown in Fig. 1.

30 Before proceeding with the detailed descrip-

tion of the apparatus and method of my invention, it should be well to note here that as defined in the claims my invention is not limited to operations upon any particular liquids or materials but instead is broadly adapted to perform blending and mixing operations upon a wide variety of materials such as can be moved to or through suitable conduits or other means. However, my method and apparatus is particularly concerned with blending or mixing liquids or liquid bearing materials. The words "liquids" or "liquid" as used in the specification and claims are intended to include broadly liquids of any and all kinds, and, also, liquids bearing solids dissolved, suspended or otherwise carried by the liquid. In this connection it should be understood that I contemplate adding any non-liquid material in powdered, granulated, jellied, or any other form to a liquid prior to passing the liquid to the blending apparatus of this invention so that the non-liquid material will be minutely mixed, intermingled, or molecularly combined in the resulting blend of liquids produced by my method and apparatus.

While as stated above my invention is broadly concerned with handling a wide variety of liquids and other materials, nevertheless, one specific use to which my apparatus and method has already found wide application is that of oil blending, and, accordingly, my invention has been illustrated and will be described in conjunction with oil blending. It should be understood in this connection that oil or other blending or mixing operations may involve a plurality of materials and that while I have illustrated and will describe in conjunction with the embodiment of my invention shown in Fig. 1, the blending of three materials, namely, bright stock, neutral stock, and pour depressant, that my apparatus may be readily adapted to blend or mix a greater or less number of materials as hereinafter described in detail.

Having reference to Fig. 1 of the drawing, the numeral 10 indicates a base of flat rectangular form which carries at one end a prime mover 12, usually of the form of an explosion proof electric motor. The main driving shaft 13 of the motor 12 is connected through a suitable coupling 14 to a straight-through shaft 16 of a reduction gear box 18 which is mounted in line with the motor 12 on the base 10. The straight-through shaft 16 of the gear box 18 is connected at its other end, through a suitable coupling 20, with the operating shaft 22 of a blending mill 24.

It will be understood that the blending mill 24 may take a plurality of forms, but it is an important part of my inventive concept that the blending mill be capable of performing a very lacerating, cutting, attriting, grinding, and milling action upon the liquids to be blended. One type of blending mill which I have found to be particularly satisfactory for my purpose is that disclosed and claimed in my prior Patent No. 1,739,360. From this patent it will be recognized that the materials to be blended are given such a lacerated intermingling in the blending mill that the result is substantially a molecular conglomerate, which word here and in the claims is intended to cover any blending or mixing action of the type wherein substantially every molecule of one material being mixed is torn from every other molecule of the same material and the molecules of the several materials after blending or mixing are a heterogeneous mass. In other words, each molecule of one material being

mixed tends to lie next to a molecule of another material being mixed rather than having two molecules of the same material engaging each other. Of course, in actual practice where one material is predominate in the blend there may be a number of molecules of this predominate material in engagement with each other, but none-the-less the blending and mixing action produced by the blending mill is such that substantially each molecule of the same material will be torn from an adjacent molecule of the same material or the action closely approaches this ideal.

The gear box 18 has a plurality of jack shafts 26 extending therefrom, usually in opposite directions, which due to the internal construction of the gear box 18 are driven at a reduced speed as compared to the straight-through shaft 16. For example, the jack shafts 26 may be driven at a speed of 200 R. P. M., whereas the straight-through shaft 16 is driven at the same speed as the motor 12, for example 1750 R. P. M. Each jack shaft 26 is connected through suitable couplings 28 and 30 with the operating shafts 32 and 34, respectively, of pumps 36 and 38 which may be mounted upon base brackets 40 and 42 secured to the base 10 of the apparatus.

The input side of the pump 36 is connected by a conduit 44 to a tank or other suitable source of supply for bright stock, which is a petroleum distillate or thinner. The output side of the pump 36 is connected through a valve 46 and a conduit 48 with a manifold 50 which extends to the intake side 52 of the blending mill 24. The conduit 48 has a flow indicating meter 54 and a flow totalizing meter 56 associated therewith. The meter 54 indicates the rate of flow of liquid through the conduit 48 whereas the meter 56 indicates the total amount of flow. The pump 38 has a by-pass 58 associated therewith and extending from the output side of the pump back to the input side. A valve 60 controls the flow of liquid through the by-pass.

It will be recognized that the valves 46 and 60 provide a very accurate control together with the meters 54 and 56 so that the exact amount of bright stock passed to the manifold 50 and into the blending mill 24, together with the pressure on the bright stock can be very accurately and quickly controlled. Closing the by-pass valve 60 tends to increase the pressure on the bright stock passed to the manifold 50, and the amount of the bright stock passed to the manifold depends upon the setting of the valve 46. Of course, usually both the valves 46 and 60 must be adjusted to achieve exactly the type of pressure and amount of flow desired.

The input conduit 62 of the pump 38 extends to a tank or other source of supply for neutral stock, which may be crude oil of a given grade and quality, and the output side of the pump 38 extends through a valve 64 to a conduit 68 which is also connected to the manifold 50. The conduit 68 has associated therewith a flow indicating meter 70 and a flow totalizing meter 72. The pump 38 includes a by-pass 74 having a valve 76 therein and which connects the input and output side of the pump 38 so that the pump together with its associated apparatus will function to supply controlled and desired amounts of neutral stock under desired pressures to the input side of the blending mill 24.

In the particular embodiment of my invention illustrated in Fig. 1 means have been illustrated to supply desired amounts of pour depressant to

the input side of the blending mill 24. Specifically, the numeral 80 indicates a pump which is driven by a V belt 82 or other means from the shaft 32. An input conduit 84 on the pump is connected to a source of supply of pour depressant and the output side of the pump 80 is connected through a valve 86 to a conduit 88 which is connected to the manifold 50. A flow indicating meter 90 and a flow totalizing meter 92 are associated with the conduit 88. Pump 80 is provided with a by-pass 89 valved by means 91.

The output side of the blending mill 24 is connected by a conduit 96, having a pressure gage 97 associated therewith, to pressure relief means of suitable nature positioned in the top of a storage tank 100. Although the pressure relief means may take a plurality of forms I have found that a suitable adjustable spray nozzle, such as indicated by the numeral 102 and having some suitable spray adjusting or adjustable flow restricting means 104 associated therewith is particularly suitable for my purpose. Usually the pressure relief means 102 are positioned at the center and in the top of the tank 100.

The top of the tank 100 is connected by a suitable conduit 106 to the intake side of a pump or blower 108 which has its output conduit 110 connected to the atmosphere or to a distillation system. Conveniently, the pump or blower 108 is of the centrifugal type and is driven from the prime mover 12 either by mounting the blower 108 on the end of the motor and extending the drive shaft 13 out both ends of the motor, or by providing pulleys 112 on the motor shaft 13 and having the pulleys drive a jack shaft extending below the motor and connected to the blower which would then be mounted on the end of the base 10.

I have found it advantageous to incorporate automatic starting and stopping apparatus with the tank 100 and this may take the form of an electric switch 116 mounted on the outside of the tank 100 and having an operating shaft extending through the side of the tank and secured to a lever 118 carrying a float 120 at its outer end. The switch 116 when operated by the raising of the float 120 serves to shut off the prime mover 12 as will be understood. A conduit 122 connected to the bottom of the tank 100 serves to remove the mixed liquids from the tank 100.

It is believed that the operation of my improved apparatus, and the practice of my new and useful method will be evident from the foregoing description. Suffice it to say here that bright stock, neutral stock, and pour depressant are supplied in controlled and desired amounts by the pumps 36, 38 and 80 to the manifold 50 and intake conduit 52 of the blending mill 24. The pressure on the materials so supplied is controlled, of course, by the valve mechanisms referred to in conjunction with the description of the pumps, and further by adjusting the means 104 controlling the back pressure action of the pressure relief means 102. The pressure on the materials during the mixing or blending operation is indicated by the pressure gage 97. The materials thus continuously passed to and through the blending mill 24 are reduced to a molecular conglomerate in the blending mill in the manner already referred to and passed still under a relatively high pressure, as for example, from between above atmospheric pressure to about 300 pounds per square inch, and usually in the neighborhood of about 100 pounds per square inch when blending oil, although many of the

advantages of the invention are retained when operating at other pressures. When blend materials other than oil I contemplate employing pressures from above atmospheric up to about 500 pounds per square inch or even more. Usually a pressure of at least 50 pounds per square inch is employed.

The effect of the application of pressure on liquids during blending and mixing is such, I believe, on the various molecules, cells, suspensoid forms, encapsulated particles and body thereof that the result is an apparent increase in the viscosity of the liquid. This causes a very different and an improved type of cutting, milling, grinding and attriting action on the liquids in the blending mill than would occur without the apparent change of viscosity.

The liquids after blending pass still under pressure to the pressure relief means positioned in the top of the tank 100 at which time they are sprayed or otherwise discharged into the tank 100 which is kept under a pressure not greater than atmospheric, and usually under a sub-atmospheric pressure by the blower 108. The sudden change from the relatively high pressure on the liquids to the relatively low or even sub-atmospheric pressure in the tank 100 causes any air, water vapor, or other gas bubbles present in the mixed liquids to substantially explode, escape, or otherwise separate from the liquids proper. The result is that the liquids substantially free of gas inclusions fall to the bottom of the tank 100 from which they may be drawn off by the conduit 122.

The gas thus separated from the liquids and positioned at the top of the tank is drawn off by the blower 108 through the conduit 106 and is discharged to the atmosphere or is passed by the blower through a suitable distillation or other system so as to draw from the gas any liquids therein or which could be formed by suitable condensation or treatment of the gas. The float 120 operating the switch 116 shuts off the motor 12 when the tank 100 becomes too full. However, when liquid is drawn from the tank 100 the float 120 drops to operate switch 116 and restart the apparatus.

Before leaving the apparatus and method illustrated in Fig. 1 and above described it should be noted that to simplify the illustration of the apparatus and to better exemplify the construction and working thereof that the exact position and form of the various conduits and tank 100 have been diagrammatically shown. In actual apparatus constructed in accordance with the principles of my invention the conduits will run in the best possible paths between the respective parts of the apparatus and will, of course, avoid any sharp right angle turns and will in general provide the best possible type of liquid conducting means. Also, I preferably arrange the conduit and piping system so that it may be completely drained from a single petcock. This is convenient for cleaning or for changing the apparatus to operations on other materials.

It should be understood that I may employ pumps incorporating automatic by-pass means with the flow of liquid being adjusted as above described by a suitable valve or valves. However, I should not be limited to the use of automatic by-pass pumps, as I may use valved by-pass, as already described, or I may use a pump having an adjustable piston travel so that the pump itself without by-passing can be adjusted to operate at the particular rate of flow desired.

Still again, I may employ a variable speed motor to drive the pump so that the rate of flow may be controlled by the motor rather than the pump.

The embodiment of my invention shown in Fig. 2 illustrates the general arrangement and construction of the apparatus when it is adapted to blend more than three, and particularly four liquids. Specifically, the numeral 10a indicates a base having a prime mover 12a mounted at one end thereof and driving a straight-through shaft of a gear box 18a. Jack shafts extending laterally from the gear box 18a serve to drive pumps 36a and 38a in the manner heretofore described. The pumps 36a and 38a are mounted on base brackets 40a and 42a. However, instead of connecting the straight-through shaft of the gear box 18a with the blending mill 24a, it is a relatively simple matter to extend the base 10 of the form of the invention shown in Fig. 1 so that room is provided on the extended base 10a for a second straight-through gear box 181a. The straight-through gear box 181a is connected to the straight-through shaft of the gear box 18a at one end and to the blending mill 24a at its other end. Thus, the blending mill 24a is still driven at the same speed as the motor 12a. The laterally extending jack shafts of the gear box 181a drive pumps 361a and 381a which are mounted upon suitable base brackets 401a and 421a secured to the base 10a. In an exactly similar manner additional base brackets can be secured to the base 10a to both extend the length of the base 10a and to provide additional laterally extending base portions so that any desired number of additional gear boxes and pumps can be added to the apparatus to blend any desired number of liquids. Of course, additional pumps such as the pump 39 in Fig. 1 can be incorporated with the apparatus of Fig. 2 if only relatively small amounts of material are to be pumped. Thus, it will be recognized that the general conception and the arrangement of my apparatus is such that it is readily adapted to modification whereby the apparatus can be adapted to handle any desired number of liquids in the blending or mixing operation.

From the foregoing, it will be recognized that the objects of my invention have been achieved by the provision of improved means and methods for minutely blending or molecularly mixing a desired plurality of liquids in controlled amounts and at controlled pressures. The method and apparatus are rapid, relatively inexpensive, and easily controlled, adjusted and operated.

While in accordance with the patent statutes, I have particularly illustrated and described certain best known embodiments of my invention, it should be particularly understood that my invention is not to be limited thereto or thereby, but that the scope of my invention is defined in the appended claims.

I claim:

1. That method of mixing liquids which comprises continuously passing a controlled and measured amount of one liquid to a mixing chamber, continuously passing controlled and measured amounts of at least one additional liquid to the mixing chamber, maintaining the liquids under a relatively high pressure in the mixing chamber, reducing the liquids to a molecular conglomerate by cutting, attriting, grinding and milling them while under pressure in the mixing chamber, continuously passing the molecular conglomerate of liquids still under pressure to a storage tank, suddenly releasing the pressure on

the conglomerate as it is discharged in spray form into the tank so that any gas bubbles present explode or escape and the gas stays at the top of the tank and the liquid conglomerate falls to the bottom of the tank, and withdrawing the gas from the top of the tank under sub-atmospheric pressure.

2. That method of mixing liquids which comprise continuously passing controlled and measured amounts of a plurality of liquids to the mixing chamber, maintaining the liquids under a pressure of over atmospheric pressure and up to about 500 pounds per square inch in the mixing chamber, reducing the liquids to a mixture by cutting, attriting, grinding and milling them while under pressure in the mixing chamber, continuously passing the mixture of liquids still under pressure to a storage tank, suddenly releasing the pressure on the mixture as it is discharged into the tank, and controlling the pressure on the system at the point of pressure release.

25 3. That method of blending oils which comprises continuously passing bright stock in controlled amounts to a mixing chamber, continuously passing controlled amounts of neutral stock to the mixing chamber, continuously passing controlled amounts of pour depressant to the mixing chamber, maintaining the liquids under a pressure of over 50 pounds per square inch in the mixing chamber, continuously reducing the liquids in the mixing chamber to a molecular conglomerate, continuously passing the liquids from the chamber to a storage chamber while still under pressure, spraying the liquids into the storage chamber so as to suddenly release the pressure thereon, and maintaining sub-atmospheric pressure in and about the spray in the storage chamber.

40 4. That method of blending oils which comprises continuously passing bright stock in controlled amounts to a mixing chamber, continuously passing controlled amounts of neutral stock to the mixing chamber, continuously 45 passing controlled amounts of pour depressant to the mixing chamber, maintaining the liquids under a relatively high pressure in the mixing chamber, continuously reducing the liquids in the mixing chamber to a molecular conglomerate by a cutting, attriting, milling and grinding action, continuously passing the liquids from the chamber to a storage chamber while still under pressure, and discharging the liquids into the storage chamber so as to suddenly release the pressure thereon.

55 5. Apparatus for mixing liquids comprising an explosion-proof motor, a reduction gear box, a straight-through shaft on the gear box connected with the motor shaft, a blending mill having its operating shaft connected with the straight-through shaft of the gear box so that the blending mill is driven at the speed of the motor, jack shafts extending laterally in opposite directions from the gear box and operating at a fraction of the motor speed, a plurality of pumps, each pump having its operating shaft connected to a jack shaft, a separate conduit extending from the inlet of each pump to a source of liquid supply, a manifold connected to the input side of the blending mill, a separate conduit extending from the manifold to the output side of each pump, a flow indicating meter and a flow totalizing meter connected with each one of said last-named separate conduit, a by-pass control connected with each of said pumps so as to control

the pressure head of liquids supplied to the blending mill, a storage tank connected to the output side of the blending mill, pressure-relief spray means for discharging the liquid into the storage tank, and means operated by the motor for removing gas from the top of the storage tank and maintaining the top of the tank under sub-atmospheric pressure.

6. Apparatus for blending liquids comprising a motor, a reduction gear box, a blending mill having its operating shaft connected with the gear box so that the blending mill is driven at the speed of the motor, jack shafts extending from the gear box and operating at a fraction of the motor speed, a plurality of pumps, each pump having its operating shaft connected to a jack shaft, a separate conduit extending from the inlet of each pump to a source of liquid supply, a manifold connected to the input side of the blending mill, a separate conduit extending from the manifold to the output side of each pump, a flow indicating meter and a flow totalizing meter connected with each one of said last-named separate conduit, a by-pass control connected with each of said pumps so as to control the pressure head of liquids supplied to the blending mill, a storage tank connected to the output side of the blending mill, a pressure-relief spray means for discharging the liquid into the storage tank, and means for removing gas from the top of the storage tank.

7. Apparatus for mixing liquids comprising a motor, a reduction gear box, a blending mill having its operating shaft connected with the gear box so that the blending mill is driven at the speed of the motor, jack shafts extending from the gear box and operating at a fraction of the motor speed, a plurality of pumps, each pump having its operating shaft connected to a jack shaft, a separate conduit extending from the inlet of each pump to a source of liquid supply, a manifold connected to the input side of the blending mill, a separate conduit extending from the manifold to the output side of each pump, a flow meter connected with each one of said last-named separate conduit, a by-pass control connected with each of said pumps so as to control the pressure head of liquids supplied to the blending mill, a storage tank connected to the output side of the blending mill, and pressure-relief spray means for discharging the liquid into the storage tank.

8. Apparatus for blending liquids comprising a motor, a reduction gear box, a blending mill having its operating shaft connected with the gear box so that the blending mill is driven at the speed of the motor, jack shafts extending from the gear box and operating at a fraction of the motor speed, a plurality of pumps, each pump having its operating shaft connected to a jack

5 shaft, a separate conduit extending from the inlet of each pump to a source of liquid supply, a manifold connected to the input side of the blending mill, a separate conduit extending from the manifold to the output side of each pump, a by-pass control connected with each of said pumps so as to control the quantity and in part the pressure head of liquids supplied to the blending mill, a storage tank connected to the output side of the blending mill, pressure-relief means for discharging the liquid into the storage tank, and adjustable flow restricting means connected with the pressure-relief means and adapted to control the back pressure.

10 9. Apparatus for blending liquids comprising a motor, reduction gear box means connected to the motor, a blending mill having its operating shaft connected with the gear box means so that the blending mill is driven at the speed of the motor, jack shafts extending from the gear box means and operating at a fraction of the motor speed, a plurality of pumps, each pump having its operating shaft connected to a jack shaft, a separate conduit extending from the inlet of each pump to a source of liquid supply, a manifold connected to the input side of the blending mill, a separate conduit extending from the manifold to the output side of each pump, a storage tank connected to the output side of the blending mill, and means for discharging the output side of the blending mill into the storage tank with a sudden release of pressure.

15 10. Apparatus for mixing liquids comprising a blending mill adapted to reduce the liquids to a molecular conglomerate by cutting, attriting, grinding, and milling, means for driving the mill at high speed, means operated by the mill driving means for continuously supplying controlled amounts of a plurality of liquids and under controlled relatively high pressures to the blending mill, a storage tank, means including a pressure relief spray continuously discharging the output of the blending mill into the storage tank, and means operated by the mill driving means for withdrawing gas from the top of the storage tank and for maintaining the inside of the tank under sub-atmospheric pressure.

20 11. Apparatus for blending liquids comprising a blending mill adapted to reduce the liquids to a molecular conglomerate by cutting, attriting, grinding, and milling, means for driving the mill at high speed, means for supplying controlled amounts of a plurality of liquids and under relatively high pressures to the blending mill, a storage tank, means for discharging the output of the blending mill into the storage tank with a sudden release of pressure, and means for adjustably controlling the flow restricting action of the discharging means.

ROBERT C. HOPKINS.
